TRANSFORMER

Frederick C. Owen, Fayetteville, N. C.

Application October 9, 1934, Serial No. 747,607

5 Claims. (Cl. 172—246)

The object of the invention is to provide a transformer in which the disadvantages due to its normally low power factor are overcome by equipping it with a reactance of a character to materially improve the power factor; to provide a construction in which the reactance is cut into and out of circuit, so that its beneficial effects may be had during load periods in the transformer without the disadvantage of the absorption of energy from the line during periods of idleness; and to provide a construction in which the operation of cutting the reactance into and out of circuit is wholly automatic, but dependent entirely on the presence of a load in the secondary.

With this object in view, the invention consists in a construction and combination of parts of which a preferred embodiment is illustrated in the accompanying drawing, wherein the figure is a diagrammatic view of the invention.

The transformer illustrated is of the step-down type, being of the kind ordinarily employed in electric welding, and being of the magnetic leakage type in which the primary 10 is wound in three sections on three different legs of the core 11. The secondary 12 is wound on the remaining leg of the core, as well as on the diametrically opposite leg over the intermediate section of the primary.

The primary is energized from a suitable source and is controlled preferably by the double-pole single-throw switch 14. The two terminals of the secondary are carried to the load, which, if the transformer be used for welding, for which it is particularly designed, will be dissipated in maintaining the arc necessary to effect the welding operation.

The normally low power factor inherent in such a construction of transformer may be materially improved by the means of a condensive reactance, which, in the illustrated embodiment, consists of capacitors 16, of which there may be a bank with the terminals connected to the terminals 16 of a double-pole switch which normally assumes an open position but which is automatically moved to closed position. The switch terminals 17, which are complementary to the terminals 16, are connected across the primary terminals of the transformer. When the switch is closed, therefore, the reactance is thrown directly across the primary, but when the switch is open, it is cut out of circuit. Thus there are provided beneficial effects of the reactance without any of the disadvantages of its use, such as the absorption

of charging current during periods of idleness of the transformer.

The operation of cutting the reactance into and out of circuit is made dependent on the transformer being under load, and to this end a supplemental coil 18 is disposed in surrounding relation to the core and its terminals are connected with an electro-magnet 19 which constitutes the actuating element for the switch. The magnet 19 is preferably an element of a stationary yoke member 20, the extremities of which, when the magnet is energized, become magnetic poles exerting a magnetic pull on an armature 21 which carries the contacts 16.

When there is no load current in the secondary of the transformer, as when the welding operation is not being performed, if the transformer be designed for welding, there is practically no magnetic leakage from the core and hence no energy is present in the supplemental coil 18. Immediately upon a load being imposed on the secondary, as when the welding operation is being carried on, the magnetic distortion taking place in the core results in a stray magnetic field which is effective to generate a current in the coil 18, which becomes effective in the magnet 19, thereby causing the switch to be operated and the reactance to be thrown into circuit with the primary, thus effecting a material improvement in the otherwise poor power factor of the apparatus. When there is no load in the secondary, as when the welding operation is discontinued, there exists practically no stray field in the transformer core and accordingly there is no current generated in the coil 18 so that the magnet 19 is then deprived of energy, preventing it from maintaining the closed position of the switch, which then drops to open position, thus cutting the reactance out of circuit, so that its employment does not represent a loss during idle periods as by the absorption of a charging current.

The invention having been described, what is claimed as new and useful is:

1. In combination with a transformer having a normally low power factor, a condensive reactance, an electrically operated switch for connecting the reactance in one of the circuits of the transformer, and a coil for generating switch actuating current but related only inductively to an element of the transformer and generating switch operating current only when the secondary is under load.

2. In combination with a transformer having a normally low power factor, a condensive reactance, a magnetic switch for connecting the re-

actance across the primary, and a coil for energizing the switch, said coil having such an induction relation to the transformer as to limit it to generating the switch energizing current only 5 when the secondary is under load.

3. In combination with a transformer having a normally low power factor, a condensive reactance, a magnetic switch for connecting the reactance across the transformer primary, and a 10 supplemental coil for energizing the switch, said coil being disposed in surrounding relation to the transformer but responsive to core leakage in the latter only when the secondary is under load.

4. In combination with a transformer having 15 a normally low power factor, a condensive reactance, a normally open magnetic switch for

connecting the reactance across the primary of the transformer, and a supplemental coil energized from the transformer only when the secondary is under load and operatively connected with the switch to energize and to actuate the 5 same.

5. In combination with a transformer having a normally low power factor, a condensive reactance, a supplemental coil disposed in surrounding relation to the transformer and rendered active only when the secondary of the transformer is under load, and a normally open magnetic switch for connecting the reactance across the primary of the transformer, said switch being energized from said coil. 10 15
